UNITED STATES PATENT OFFICE.

JOSEPH L. HILLER, OF MATTAPoisETT, MASSACHUSETTS.

SCREENING SURFACE.

Application filed August 20, 1921. Serial No. 494,025.

To all whom it may concern:

Be it known that I, JOSEPH L. HILLER, a citizen of the United States, residing at Mattapoisett, in the county of Plymouth and State of Massachusetts, have invented certain new and useful Improvements in Screening Surfaces, of which the following is a specification.

This invention relates to improvements in screening surfaces adapted not only to general but also to special purposes and especially to the selective types of screens.

The object of the invention is to produce a screening surface which shall so reticulate the material to be screened as to promptly and favorably present all of the material in such a manner as to cause, in the shortest possible time, the elimination of those pieces small enough to pass through the screen and, therefore, in screening, to promote those valuable advantages of maximum capacity, thoroughness of classification and reduction in cost of operation resulting from the improved qualities of the screening surface. Another important object to be attained is to secure the passage through the screen of flat pieces, sufficiently thin to pass through the screen edgewise and yet so wide as to prevent their passage through the screen flatwise.

My invention consists of a screen of the cascade type, in which the material passing over the successive cascades is tumbled and stirred so as to present the pieces of material in constantly changing new arrangements, thus quickly presenting in a favorable position for discharge each piece small enough to be eliminated.

Referring to the drawings, Fig. 1 represents a perspective view of a portion of such a screening surface as is contemplated by my invention. Fig. 2 shows a plan view of such a screening surface and Fig. 3 represents a side elevation of Fig. 2.

Referring now to the several views of the drawing, the numeral 2 indicates projecting members, according to my invention, on the first and on the third series of cascades in which series 3 represents the cascading portion of the first and the third series of cascades and which portions (3) are of the type of the prior art. The projections marked 2^a are, likewise, representative of a feature of my invention being shown on the second and fourth series of cascades. Similarly 3^a shows cascading portions of the

old types on the second and fourth series of cascades. The spacing washers 4 shown in Fig. 1 are not shown in Fig. 2. Similarly the rods 5 on which the screen shown in Fig. 1 is assembled are omitted from Fig. 2 and Fig. 3.

It will be noted that in the arrangement which I have shown, the wire screen bars have a projecting cascading member on each alternate cascading portion of the screen bar, and that these screen bars are so assembled that a projecting cascading member alternates with a plain cascading member in each cascading series extending across the screen.

It is evident that the proportion of projecting members may be varied and that the length of the projecting members may be altered to suit the character of the material to be classified.

It will be observed that the projecting members of the screen are so tapered that, longitudinally with the travel, the thickness of these members is decreased and the width of spaces between said members is increased thereby, and by thus avoiding the possibility of narrowing the spaces in the direction of travel of material, the screen is free from clogging. Although the taper of the screen bars tends to make a clean working and effective screen, this feature is not claimed as a part of this invention, except as to the projecting members.

In operation, the pieces of material pass longitudinally over the screen and the cascading effect upon the material brings fresh pieces in contact with the screening surface. The projecting members have two functions. The first is useful in general screening operations because of its action in elevating or pushing up through the mass those pieces of material which are of larger size. The action of these projecting members will, in effect, be similar to the action of a series of parallel bars arranged lengthwise of the travel and intermittently projected upwardly through the mass, thus lifting the larger pieces of material and maintaining them on top of the blanket of material passing over the screen. The second function of these projecting members is of advantage in separating the thin flat pieces from the pieces having a cubical or spherical tendency for, as a flat piece passes over the screening surface between the cascades, the flat side will usually lie upon the screen

and in passing over one of these projections the piece will be tilted to one side or the other, in which process it is turned up edge-wise and if thin enough will pass through 5 the screen. If such a flat piece happens to flow between two of these projecting members on one cascade it will, on account of the alternate longitudinal occurrence of the projections, come in contact with a projecting 10 member on the next, or some subsequent, cascade and thus be tested and classified. It will thus be seen that the alternate arrangement of the projections is such as to insure or facilitate the proper reticulation of 15 each piece of material, so as to secure its proper classification. It will also be observed that the larger pieces of material which are lifted from the general screening surface by the projecting members will be 20 delivered to the projecting members on the successive cascades with scarcely any opportunity of touching the intervening general surface of the screen.

This type of screening surface is adapted 25 for use either as a relatively flat screen which may be stationary and so inclined as to permit screening by the action of gravity, or it may be given a reciprocating motion to facilitate the passage of material over a screen 30 which is less inclined, or it may be curved into a cylinder, or it may be adapted to suit the conditions of variously arranged special screens.

The type of construction which I have 35 shown is well suited to manufacturing methods employing electric welding apparatus which results in a cheap, rugged and reliable product. The screen illustrated in the drawings is provided with wire bars spaced 40 apart by means of washers on the rods which

pass through loops in the wires. This looping of the longitudinal wires is not, however, an essential construction and, in some instances, may not be as cheap or as desirable as a bar having some other form of 45 support. While I show a screen made from wire, my invention is not limited to wire screens, for castings, forgings, stampings or other forms of construction may be utilized with good effect. 50

What I claim is:

1. A screen consisting of bars, being formed with a series of bends in planes perpendicular to the general surface of said screen and said bars having projections intermediate, longitudinally of certain of said bends and continuing the planes, on one side of said bends a distance in excess of the height of said projections above the planes 55 of the screen on the other side of said bends. 60

2. A screen consisting of a series of cascades, on bars, arranged in rows, transverse of said bars, with projections on alternate bars extending forward, in the direction of said cascades, said projections extending 65 from points approximately in line with the brows of said cascades.

3. A screen consisting of a series of cascades, on bars, arranged in rows, transverse of said bars, having tapered projections on 70 non-adjacent bars, extending forward, in the direction of said cascades, said projections extending from points approximately in line with the brows of said cascades.

In testimony whereof I have affixed my 75 signature in the presence of two witnesses.

JOSEPH L. HILLER.
